UNITED STATES PATENT OFFICE.

GILBERT REYNOLDS, OF RIDGEBURY, CONNECTICUT.

COFFIN.

SPECIFICATION forming part of Letters Patent No. 350,155, dated October 5, 1886.

Application filed February 12, 1886. Serial No. 191,700. (No model.)

To all whom it may concern:

Be it known that I, GILBERT REYNOLDS, a citizen of the United States, residing at Ridgebury, in the county of Fairfield and State of Connecticut, have invented certain new and useful Improvements in Burial-Caskets; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

The invention relates to burial-caskets; and the novelty consists in the construction, arrangement, and adaptation of parts which comprise the lid-fastening devices, as will be more fully hereinafter set forth and specifically pointed out in the claims.

The invention is designed as an improvement upon the device patented to me January 26, 1886, and numbered 334,808.

In the present device the groove in which the locking-rib travels is inclined, and the locking-rib has two locking projections, one on each side of the rib, which engage inclines upon the coffin-body casting. The lid carrying the rib proceeds down an incline which is gradual, and the locking-key has a novel construction.

The invention is fully illustrated in the accompanying drawings, which form a part of this specification, and in which—

Figure 1 is a vertical section. Fig. 2 is a top plan view of the body-casting and a section of the body of the casket. Fig. 3 is a reverse plan view of said casting detached. Fig. 4 is a bottom plan view of the lid-casting. Fig. 5 is a bottom plan view of the holding-catch. Fig. 6 is a cross-section.

Referring to the drawings, in which similar letters of reference indicate like parts in all the figures, A designates the body of the casket, and B the lid thereof.

C designates the body-casting, having a longitudinal groove, c, which is inclined in the direction of the locking-recess c'.

D designates the lid-casting, having a longitudinal rib, d, with inclined edge d', and having a locking-lug, d'', upon each side of said rib. The recess c' is of a size to receive the rib D and its lugs, and the casting C has two flanges, c'', separated by a slot, c', the slot serv-

ing to receive the rib d, and the flanges c'' serving to engage the lugs d''. The lower face of these flanges c'' have an incline, c', against which each of the lugs d'' abut when the lid B has reached its seat. I deem this construction important in allowing the lid B to approach its seat by means of a gradual incline, and by allowing the lid to be applied without perceptible noise or jar. As the lid is placed upon the casket, the rounded lower part of the rib d rests in the groove c. As the lid is forced in the direction of the foot of the casket, it is supported by these ribs (of which there are ordinarily four, two on a side) until the locking-lugs pass into the aperture c', when the inclined surface d' of the ribs d serve to continue the gradual descent. The further descent brings the lugs d'' against the inclines c', where they become wedged, the cloth between the lid and body serving with a spring-force to hold them thus and to make a tight noiseless connection.

F designates a spring-catch, having a locking pin or shoulder, f, and a slot, f''. It is secured upon the under face of the lid over a recess, g, formed therein. A screw at one end holds the catch immovably to the lid, while a screw through the slot at the other end allows the catch to have a limited longitudinal movement. A thumb-plate, f'', allows the greater area of the spring-body to be forced up into the recess g to disengage the pin f from its socket g' in the body of the casket.

What I claim as new is—

1. In a burial-casket, the combination, with a body, A, having an inclined way, c, a locking-recess, c', and inclines c'', with which the locking-lugs of the lid engage when the lid has found its seat, of the lid having locking-ribs with inclined surface and locking-lugs, as set forth.

2. In a burial-casket, A B, having recesses g and g', as shown, the combination, with the castings C D, as described, of the spring-catch F, having slot f'', catch f, and thumb-plate f'', all arranged and adapted to serve as set forth.

In testimony whereof I affix my signature in presence of two witnesses.

GILBERT REYNOLDS.
